W. J. HOGUE

WELL REAMER

Filed Dec. 19, 1921

UNITED STATES PATENT OFFICE.

WILLIAM J. HOGUE, OF KANSAS CITY, MISSOURI, ASSIGNOR TO PETROLEUM RECOVERY CORPORATION, OF NEW YORK, N. Y., A CORPORATION OF DELAWARE.

WELL REAMER.

Application filed December 19, 1921. Serial No. 523,304.

To all whom it may concern:

Be it known that I, WILLIAM J. HOGUE, a citizen of the United States, and resident of Kansas City, county of Jackson, State of 5 Missouri, have invented a certain new and useful Improvement in Well Reamers, of which the following is a complete specification.

The present invention relates to apparatus 10 for use in the reaming out and cleaning of wells, and the principal object in view is to provide a simple and inexpensive device for efficient operation in the reaming out of the bottoms of wells for the purpose both of 15 cleaning the same and also enlarging the reservoir space around the well bottom.

Accordingly, I have devised a novel form 20 of reaming device which is adapted to be attached to the lower end of the pump tubing, and actuated by rotation of the tubing for effecting the reaming operation by the 25 centrifugal movement of a pair of reaming cutters which are pivotally suspended for free outward swinging movement in opposite directions.

With this general object in view, the invention will now be described by reference to the accompanying drawing, illustrating one form of construction which I have devised for embodying the proposed improvements, after which the novel features therein 30 will be particularly set forth and claimed.

In the drawing—

Figure 1 is a sectional perspective view, 35 illustrating a pumping apparatus having associated therewith a reamer device constructed in accordance with the present invention;

Figure 2 is a view similar to the lower portion of Figure 1, but illustrating the reamer cutters spread into different operative positions;

Figure 3 is an enlarged longitudinal sectional view of the reamer device; and

Figures 4 and 5 are transverse sections taken on the lines IV—IV and V—V of Figure 3.

Referring now to the drawing in detail, 50 this illustrates the improved reamer as comprising a pair of mating reaming cutters 10 pivotally connected at their upper ends, as indicated at 12, to the opposite sides of a head-piece 14 (see Figure 3). Depending centrally from this head-piece 14 and extending between the cutter members 10 is a

longitudinal stem portion 15 terminating at its lower end in a drill bit member 16, the upper shoulder portion of which is adapted to shield or protect the lower ends of the cutter members 10 when the latter are in collapsed position, as illustrated in Figure 3, which would be the position assumed by the parts on lowering of the same down into the well sands for the reaming or cutting operation (see Figure 1). The outer face 60 of each of the reaming cutter members 10 is provided with a plurality of helical cutting edges 17 for producing a proper efficient cutting action in the circular motion of the cutters when operating as illustrated in 70 Figure 2.

The head-piece 14 is adapted to be attached by means of a collar 18 or the like to the lower end of a string of pump tubing 20 forming a part of a pumping apparatus operated from the top of the well, as shown in Figure 1, where the pump tubing 20 is shown as rotatably supported from a swivel member 21 suspended from a cable 22 adapted to be operated from the usual winch apparatus (not shown) for taking up or letting down the tubing. The upper end of the tubing 20 is slidingly fitted through the hub of a bevel gear 24 journaled upon a suitable framework 25 located at the top of the well, said bevel gear meshing with a bevel pinion 26 on a shaft 27 journaled in bearings 28 on said framework 25, which shaft also carries a pulley 29 adapted to be driven in any preferred manner. Above the gear 24, a collar 30 is clamped to the tubing 20 by means of a clamping screw 31, said collar being formed with a projection 32 having a slideable engagement with a post 33 projecting vertically 90 from the outer margin of the gear 24; in this manner, the gear 24 is adapted to drive the tubing 20, for imparting rotary movement thereto, while at the same time allowing the tubing to be raised or lowered 95 through the operation of the cable 22.

The use of the present improved device is designed especially for the reaming out and cleaning of the bottoms of oil wells, in order to renew the flow of the oil in those wells which have apparently become exhausted. It is well known that practically all oil wells undergo a "shooting" operation by means of a high explosive for the purpose of cracking the sands around the bottom of the well and starting the flow of 100 105 110

the oil. This operation sometimes ruins what might otherwise have been a good flowing well, on account of the packing and sealing of the sand around the walls of the well and thereby effectually preventing any flowing or seeping of the oil into the bottom of the well. Whenever such a packed and sealed condition occurs, either by the shooting of the well or the accumulation 10 of paraffin or asphalt around the walls of the well, the only effective means for removing such obstructions to the flow of the oil is to cut away and remove all such crusted formations, thereby restoring the 15 walls of the bottom of the well to that natural condition of the sand which will permit the normal flow and seepage of the oil into the reservoir space existing at the bottom of the well or pump tubing. Such 20 is the function of the present apparatus, in the operation of which the improved device is attached to the lower end of the tubing 20 and let down to the bottom of the well, and the driving mechanism attached to the upper end of said tubing for rotating the tubing and the reaming cutters; and as the device is let down into its operative position, it will be observed that the drill bit member 16 will protect the 25 lower ends of the cutter members 10 and facilitate the feeding of the device into the sand. Since the reamer cutters 10 are pivoted at points 12 which are at opposite sides of the longitudinal axis of the stem 30 15, and hence on opposite sides of the axis of rotation of the device, it will be understood that after a given speed of rotation has been attained, the cutter members 10 will spread outwardly under the action of 35 centrifugal force, in the manner illustrated in Figure 2. This results in the gradual cutting down of the walls around the bottom 40 45 50 55 60 65 70 75 80 85 90 95

of the well, and thus effectually removing the compacted deposits above referred to, and also increasing the size of the reservoir space so that a larger seepage area is provided around the bottom of the well as well as a materially larger reservoir or basin for the accumulation of the oil.

It is thus apparent that a simple, practical and efficient device has been provided for carrying out the desired objects of the invention, and while I have illustrated and described what I now regard as the preferred form of construction, I desire to reserve the right to make such changes as may fairly fall within the scope of the appended claims.

What I claim is:

1. In combination with a well pump tubing, a reaming device adapted to be attached to the lower end of said tubing and comprising an axial stem portion and a pair of mating reaming cutters pivotally suspended on opposite sides of said stem portion for free outward swinging movement on rotation of said tubing, said stem portion terminating at its lower end in a drill bit element adapted to shield the lower ends of the cutters in the lowering of the device to operative position.
2. In combination with a well pump tubing, a reaming device adapted to be attached to the lower end of said tubing and comprising a pair of mating reaming cutters provided with helically arranged cutting edges, said cutters being pivotally suspended for free outward swinging movement about centers at opposite sides of the longitudinal axis of said tubing.

In witness whereof I hereunto affix my signature.

WILLIAM J. HOGUE.
